CONSTANT OTTEVAERE, OF SPOKANE, WASHINGTON

FLUID CURRENT MOTOR

Application filed August 6, 1927. Serial No. 211,163.

My present invention relates to improvements in fluid current motors or air motors designed for the purpose of taking advantage of air currents or movements of the wind, as well as for artificial drafts.

The invention involves a tower in which is enclosed a rotary mechanism designed to be operated by the natural movement of air currents or wind, for the purpose of producing power that may be transmitted to a place for use as desired. The tower or enclosure for the air motor is of cylindrical sectional form, the diameters of the cylindrical sections being reduced from bottom toward the top of the tower. Within the tower, a sectional spirally arranged vane is utilized in each one of the tower sections in connection with a sectional driving shaft, and means are provided for directing the air currents either natural or artificial, to the interior of the tower for operating the spirally arranged impellers or vanes on the shaft sections.

The invention consists in certain novel combinations and arrangements of parts as will hereinafter be more fully set forth and claimed.

In the accompanying drawings, I have illustrated one complete example of the physical embodiment of my invention wherein the parts are combined and arranged according to the best mode I have so far devised for the practical application of the principles of my invention.

Figure 1 is a vertical sectional view of the tower or housing of the motor showing the spiral vanes and sectional driving shaft within the tower;

Fig. 2 is an exterior view of the tower;

Fig. 3 is an enlarged detail view of one of the inlet doors and its transom used for permitting the admission of air currents to the tower;

Fig. 4 is a detail view showing one of the rollers for supporting the base member of the tower;

Fig. 5 is a horizontal sectional view at line 5-5 of Fig. 2; and

Fig. 6 is a detail sectional view of one of

the clutch devices between the sections of the driving shaft.

In carrying out my invention, I utilize a series of cylindrical walls here shown as four in number, and designated 1, 2, 3 and 4. The largest cylinder 1, which is the base cylinder, is rotatable, and the cylinders 2, 3 and 4 superimposed thereon are of successively diminishing diameter, and the topmost cylinder 4 is open at its upper end. Between the cylinders are arranged conical shaped tops 5, 6 and 7, the top 5 projecting outwardly over the rotatable base section 1, and the succeeding conical top sections 6 and 7 projecting at their lower edges over the cylinders 2 and 3. The three cylinders 2, 3 and 4 together with the conical shaped top 5 are all supported from the ground by interior braces 8 which have foundation members 9 properly embedded in the ground, and the rotatable base section 1 is supported to revolve under the conical top 5.

Within the tower is a centrally located sectional drive shaft comprising a series of sections, here shown as three and designated 10, 11 and 12. At the base a thrust bearing 13 is provided, and a gear housing 14 arranged within the brace members 8 is provided with a bearing 15 at the upper end of the conical top 49 of the housing. Spider frames 16 are provided for properly supporting the sections of the driving shaft within the tower, and between the sections of the shaft are provided clutch housings as 17. These housings are rigid with the spider frames, and within the housings are toothed clutch members are gear rings 18 and 19 secured on the adjoining ends of the shaft sections. In connection with the clutches, I utilize ball bearings as 20 to insure smooth operation of the shaft sections, and it will be apparent that the shaft sections may be connected or disconnected at will through the agency of these clutch devices. For operating the clutches, I provide each clutch device with a cam member as 21 adapted to coact with a flange 22 on the upper clutch member as 18, and this cam member is carried on a rock shaft or cam shaft 23. The shaft extends horizontally and out through one of

the conical tops, and at its outer end is provided with a cam arm 24 to which is attached a pull cord or cable 25, and this cable extends down to and is wound upon a drum or other device 26. By pulling on the cord or cable 25, it will be apparent that the cam shaft may be rocked to cause the cam 21 to turn and elevate the shaft section directly above it. In Fig. 6, one of the clutch devices is shown open with the cam 21 engaged under the flange 22 and holding the shaft sections separated. By means of the clutches, the shaft sections may be separated or disconnected in order that the wind currents may act only to drive one, two or three of the shaft sections.

Each of the shaft sections is provided with a spiral vane as 27, 28 and 29, and each of these vanes has an outer downwardly extending flange 30. The lower vane 27 is larger in diameter than the succeeding vanes, and the intermediate vane 28 is larger in diameter than the top vane 29.

These vanes are instrumental in turning the shaft sections, and the bottom section 10 is provided with a driving pinion 31 that engages a driven gear 32 on the driven shaft 33, and this shaft is provided with suitable bearings, and a pulley 34 from which power 30 may be transmitted by a belt, and used in suitable manner. The gearing just described is enclosed within the housing 14, and power is transmitted to the gearing through the rotation of the shaft sections.

35 The base cylinder 1 as heretofore pointed out, is rotatable, and is supported by means of a series of rollers 35 journaled on stud shafts 36 that project from the exterior of the base cylinder near its lower edge. These 40 rollers are adapted to travel upon an annular track 37, and at its upper edge the base cylinder revolves within another annular track 38, and rollers 39 are provided for co-action with this annular track.

45 The base cylinder is provided with a plurality of doors 40 located in openings 41 and pivoted on trunnions 42, 42. The openings 41, as seen in Fig. 5, occupy approximately one-half of the circumferential area 50 of the base cylinder 1, and the doors 40 are pivoted on the trunnions 42 that form a vertical axis for turning of the doors, as indicated in Fig. 5. The doors may be turned at various angles to direct air currents into 55 the interior of the base cylinder, and the base cylinder itself may be turned or adjusted so that the openings 41 will face the direction from which the wind is blowing. Above each door is provided a transom 43, which 60 has a horizontal hinge on pins 44, and these transoms are designed to control the openings 45 in the base cylinder. The transoms are designed to swing inwardly as indicated in Fig. 1 by dotted lines, and when swung 65 inwardly, they permit air currents to enter

below the conical roof or top 5, and these air currents are directed toward the spiral vanes.

To assist in directing the air currents to the interior of the base cylinder, I provide a pair of guide plates or shields 46 and 47 which are hinged on vertical hinges 48 on the exterior face of the base cylinder 1. As seen in Fig. 5, these guide plates may be swung to position to guide or deflect the air currents toward the openings 41 in the base cylinder, thus utilizing air currents that might otherwise pass by the base cylinder. The air currents entering through the openings in the base cylinder pass upwardly between the conical shaped roof or top 5 and the conical top 49 of the gear housing 14, and in this manner the air currents are directed to the spiral vanes of the shaft sections to rotate the vanes and the shaft sections within the tower. Associated with the conical tops 6 are braces 50, which are arranged around the inner face of each of these conical tops, and these braces which are spaced apart, also form guides for the air currents to prevent swirling motion of the air currents. By thus straightening out the movement of the air currents, these braces or guides direct the air currents in straight lines against the succeeding spiral vanes, and the vanes as a result of this direction of the air currents, are rotated efficiently.

Beneath the conical tops 6 and 7, I arrange doors 51 which are hinged at 52 to swing inwardly from the openings 53 in the upper edge of each of the cylinders 2, 3 and 4. These doors 51 swing inwardly as indicated by dotted lines in Fig. 1, and as they are arranged between the spaced guide plates or braces 50, they permit entrance of air currents and these air currents are directed in straight lines by the spaced braces.

It will be apparent that the movement of the air currents through the openings 41 causes a draft in an upward direction through the entire length of the tower. As the rising air currents impinge against the spiral vanes, the motor performs the function of a turbine, and the shaft sections which are coupled together are thus revolved. Between the turbine sections, the air currents are straightened out by the presence of the braces or guides 50, and it will be seen that after leaving these guides, the air currents are directed in straight lines, and they impinge against the surfaces of the spiral vanes, thus performing the functions of a turbine. One or more of the shaft sections may be thrown out of use by manipulating the clutch devices, or all of the shaft sections may be utilized when sufficient power is provided in the air currents.

Having thus fully described my invention,

what I claim as new and desire to secure by Letters Patent is—

The combination in a motor comprising an air tower having a rotary base cylinder with openings therein and doors to regulate said openings, adjustable guide plates on said cylinder for directing air currents toward said openings, and a series of superimposed stationary cylinders of successively reduced diameters, of a sectional driving shaft journaled within the tower, clutch devices between the sections of said shaft, spiral vanes of successively reduced diameters on said shaft, and power transmitting mechanism operated from said shaft.

In testimony whereof I affix my signature.

CONSTANT OTTEVAERE.
